UNITED STATES PATENT OFFICE.

RONALD A. McCANN, OF SWISSVALE, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Application filed July 29, 1926. Serial No. 125,762.

My invention relates to railway traffic controlling apparatus, and particularly to apparatus of the type comprising train-carried governing means controlled by energy received from the trackway. More particularly my present invention relates to the trackway portion of such apparatus.

I will describe one form of apparatus embodying my invention, and will then point out the novel features thereof in claims.

The accompanying drawing is a diagrammatic view showing one form of apparatus embodying my invention.

Referring to the drawing, the reference characters 1 and 1^a designate the track rails of a railway track over which traffic moves in both directions. These rails are divided by insulated joints 2 into a plurality of track sections of which only one section A—B is shown in the drawing. The section A—B is one section of a system of the type known as absolute permissive block signaling, so that a westbound signal S² and an eastbound signal S³ are located at point A, whereas a westbound signal S¹ and an eastbound signal S⁴ are located at point B. These signals are controlled in accordance with absolute permissive block signaling, and for this purpose the signal S² is provided with a signal relay F², which is controlled by traffic conditions to the west of the section A—B, while the signal S⁴ is provided with a signal relay F⁴ which is controlled by traffic conditions to the east of the section A—B. These two relays are normally energized, but each relay is de-energized when the territory through which it is controlled is occupied by a train. Signal S³ is provided with a normally de-energized stick relay E³ which becomes energized when an eastbound train passes signal S², and remains energized until after such train has passed point B. Located at point B is a normally de-energized relay P, which repeats the condition of the stick relay E³, and is therefore energized or de-energized according as relay E³ is energized or de-energized.

All of these relays are controlled in accordance with absolute permissive block signaling, which system is well understood and need not be described in the present application.

Located at an intermediate point X in the section A—B is a westbound train order signal C and an eastbound train order signal D. Each of these signals is manually controlled and normally indicates proceed but may be placed at stop by the operator when it becomes necessary to stop a train for the purpose of delivering orders to the train crew. Signal C controls a contact 3^c which is closed only when the signal indicates proceed, and signal D controls a similar contact 3^d which is likewise closed only when the signal indicates proceed.

Means are provided for supplying the section A—B with train governing current, and, as here shown, this means comprises circuits by which "local current" is supplied to the rails of the section in parallel. For this purpose an impedance 5 is connected across the rails adjacent point A, an impedance 8 is connected across the rails adjacent the point B, and two impedances 6 and 7 are connected across the rails adjacent the point X. Local current is supplied by transformers T¹, T², T³, and T⁴, the primaries 11 of which are all supplied with energy from a transmission line 13—13^a, which in turn is connected with a generator G.

Referring first to transformer T¹, the primary 11 of this transformer is constantly connected with the transmission line 13—13^a, and the secondary 10 is provided with a normally closed circuit which passes from the left-hand terminal of this secondary through back contact 4—4^b of relay E³, impedance 6, track rails 1 and 1^a in multiple from point X to point A, impedance 5 and contact 9 of relay F² to the right-hand terminal of secondary 10 of transformer T¹. The primary 11 of transformer T³ is provided with a circuit which passes from line wire 13, through contact 12 of relay F², contact 3^c operated by train order signal C, and the primary 11 of transformer T³ to line wire 13^a. The secondary of transformer T³ is provided with a normally closed circuit which passes from the left-hand terminal of this secondary, through impedance 8, track rails 1 and 1^a in multiple from point B to point X, impedance 7 and back contact 14—14^b of relay P to the right-hand terminal of the secondary 10. It will be seen, therefore, that if relay F² is energized and relay E³ is de-energized west-

bound train governing current will be supplied to the rails between points A and X, and that if relay F² is energized and relay P is de-energized and train order signal C is in the clear position, westbound train governing current will also be supplied to the rails between points B and X.

The primary 11 of transformer T⁴ is constantly connected with the transmission line 13-13^a, and the secondary 10 of this transformer is provided with a normally open circuit which passes from the left-hand terminal of the secondary through contact 15 of relay F⁴, impedance 8, track rails 1 and 1^a in multiple from point B to point X, impedance 7 and front contact 14-14^a of relay P to the right-hand terminal of secondary 10. Transformer T² is provided with a normally closed primary circuit which passes from line wire 13 through contact 16 of relay F⁴, contact 3^b operated by signal D and the primary 11 of transformer T² to line wire 13^a. The secondary circuit for transformer T² is normally open, and this circuit passes from the right-hand terminal of the transformer secondary through front contact 4-4^a of relay E³, impedance 6, track rails 1 and 1^a in multiple from point X to point A, and impedance 5 to the left-hand terminal of secondary 10. It will be seen, therefore, that if signal relay F⁴ is energized and repeater relay P is energized eastbound train governing current will be supplied to the rails between points X and B, whereas if relays F⁴ and E³ are both energized and train order signal D is in the clear position, eastbound train governing current will also be supplied to the rails between points A and X.

The trackway apparatus herein shown and described is suitable for co-operation with train-carried governing means in such manner that when the train occupies a stretch of track which is being supplied with train governing current the governing means causes a less restrictive indication, such as "proceed", to be received on the train, and when the train occupies a stretch of track which is not supplied with train governing current a more restrictive indication, such as "stop", is received on the train.

As shown in the drawing, the apparatus associated with section A-B is free from the influence of trains, and signals C and D are both in the clear position, so that westbound train controlling current is supplied to the rails of the section throughout its length. That is to say, a westbound train passing through the section will not affect relays E³ or P, and so this train will receive train governing current as long as it is in the section. If, however, traffic conditions to the west of the section A-B are unsafe, relay F² will be de-energized, so that

the supply of westbound train governing current between points A and X will be discontinued at contact 9 of relay F², and the supply of westbound train governing current between points X and B will be discontinued at contact 12 of relay F². If relay F² is energized and train order signal C is at stop, the supply of westbound train governing current between points B and X will be discontinued, but the supply of this current between points X and A will not be affected and so a westbound train between the two latter points will not be stopped.

I will now assume that an eastbound train enters section A-B. This train will cause relays E³ and P to become energized, thereby discontinuing the supply of westbound current at back contact 4-4^b of relay E³ and back contact 14-14^b of relay P. The circuit for supplying eastbound train governing current between points X and B will be closed at front contact 14-14^a of relay P, and the circuit for supplying eastbound train governing current between points A and X will become closed at front contact 4-4^a of relay E³. If, however, relay F⁴ is de-energized, the supply of eastbound train governing current will be discontinued at contacts 15 and 16 of this relay, and so the closing of relays E³ and P will be ineffective in so far as the supply of this current to the track rails is concerned. If relay F⁴ is energized and train order signal D is at stop, the supply of eastbound train governing current between points A and X will be discontinued, but the supply of this current between points X and D will not be affected and so an eastbound train between the two latter points will not be stopped.

Although I have herein shown and described only one form of apparatus embodying my invention, it is understood that various changes and modifications may be made therein within the scope of the appended claims without departing from the spirit and scope of my invention.

Having thus described my invention, what I claim is:

1. In a railway train control system comprising a section of track carrying both westbound and eastbound train movements, a normally energized signal relay controlled by traffic conditions to the west of said section, a second normally energized signal relay controlled by traffic conditions to the east of said section, a normally de-energized stick relay closed when an eastbound train occupies the section, and a normally de-energized repeater relay closed when said stick relay is closed; the combination with the aforementioned instrumentalities of two train order signals located at an intermediate point in said section for governing eastbound and westbound movements respec-

tively, and means controlled by said relays and by said signals for supplying train governing current to the rails of said section.

2. In a railway train control system comprising a section of track carrying both westbound and eastbound train movements, a normally energized signal relay controlled by traffic conditions to the west of said section, a second normally energized signal relay controlled by traffic conditions to the east of said section, a normally de-energized stick relay closed when an eastbound train occupies the section, and a normally de-energized repeater relay closed when said stick relay is closed; the combination with the aforementioned instrumentalities of two train order signals located at an intermediate point in said section for governing eastbound and westbound movements respectively, means controlled by said first-mentioned signal relay for supplying westbound train governing current to the rails of said section from said intermediate point to the west end of the section, means controlled by said first-mentioned signal relay and by the westbound train order signal for supplying westbound train governing current to the rails of the section from the east end to said intermediate point, means controlled by said second-mentioned signal relay and by said repeater relay for supplying eastbound train governing current to the rails of the section from said intermediate point to the east end of the section, and means controlled by said second-mentioned signal relay and by said stick relay and by said eastbound train order signal for supplying train governing current to the rails of the section from the west end to said intermediate point.
3. In a railway train control system comprising a section of track carrying both westbound and eastbound train movements, a normally energized signal relay controlled by traffic conditions to the west of said section, a second normally energized signal relay controlled by traffic conditions to the east of said section, a normally de-energized stick relay closed when an eastbound train occupies the section, and a normally de-energized repeater relay closed when said stick relay is closed; the combination with the aforementioned instrumentalities of an impedance 5 connected across the rails adjacent the west end of said section, an impedance 8 connected across the rails adjacent the east end of said section, and two impedances 6 and 7 connected across the rails at an intermediate point in said section, a transformer T^1 having its primary constantly supplied with energy and having its secondary connected with the mid points of impedances 5 and 6 through a front contact of said first-mentioned signal relay and a back contact of said stick relay, a transformer T^4 having its primary constantly

supplied with energy; a secondary circuit for said transformer T^4 connected with mid points of impedances 7 and 8 and including a front contact of the second-mentioned signal relay and a back contact of said repeater relay, a transformer T^2 having its primary supplied with energy from a front contact of said second-mentioned signal relay, a secondary circuit for transformer T^2 connected with the mid points of impedances 5 and 6 through a front contact of said stick relay, a transformer T^3 having its primary supplied with energy through a front contact of said first-mentioned signal relay, and a secondary circuit for transformer T^3 connected with the mid points of impedances 7 and 8 through a back contact of said repeater relay.

4. In a railway train control system comprising a section of track carrying both westbound and eastbound train movements, a normally energized signal relay controlled by traffic conditions to the west of said section, a second normally energized signal relay controlled by traffic conditions to the east of said section, a normally de-energized stick relay closed when an eastbound train occupies the section, and a normally de-energized repeater relay closed when said stick relay is closed; the combination with the aforementioned instrumentalities of means for supplying westbound train governing current to the rails of said section between the west end of the section and an intermediate point when said first-mentioned signal relay is energized and said stick relay is de-energized, means for supplying westbound train governing current to the rails of said section between the west end of the section and an intermediate point when said first-mentioned signal relay is de-energized and said stick relay is energized, means for supplying eastbound train governing current to the rails of said section between said intermediate point and the east end of the section when said first-mentioned signal relay is energized and said repeater relay is de-energized, means for supplying eastbound train governing current to the rails of said section between the east end of the section and said intermediate point when said second-mentioned signal relay is energized and said repeater relay is energized, and means for supplying eastbound train governing current to the rails of said section between said intermediate point and the west end of the section when said second-mentioned signal relay and said stick relay are both energized.

5. In combination, a section of railway track over which traffic moves in both directions, two train order signals located at an intermediate point in said section for governing eastbound and westbound movements respectively, means controlled by traffic conditions to the west of said section for supplying train governing current to the rails from said intermediate point to the west end of the section, means controlled by traffic conditions to the west of said section and by said westbound train order signal for sup-

plying westbound train governing current from the east end of the section to said intermediate point, means controlled by traffic conditions to the east of said section for supplying eastbound train governing current to the rails from said intermediate point to the east end of the section, and means controlled by traffic conditions to the east of said section and by said eastbound train order signal for supplying eastbound train governing current to the rails from the west end of the section to said intermediate point.

6. In combination, a section of railway track, a train order signal located at an intermediate point in said section, means controlled by traffic conditions in advance of said section for supplying train governing current to the rails from said signal to the exit end of the section, and means controlled jointly by said signal and by traffic conditions in advance of the section for supplying train governing current to the rails from the entrance end of the section to said signal.

In testimony whereof I affix my signature.
RONALD A. McCANN.
